UNITED STATES PATENT OFFICE.

SYLVANUS D. LOCKE, OF BRIDGEPORT, CONNECTICUT, ASSIGNOR TO THE LOCKE STEEL CHAIN COMPANY, OF BRIDGEPORT, CONNECTICUT.

APPARATUS AND PROCESS FOR MAKING CHAINS.

Application filed March 1, 1923. Serial No. 622,092.

To all whom it may concern:

Be it known that SYLVANUS D. LOCKE, a citizen of the United States, and resident of Bridgeport, in the county of Fairfield and State of Connecticut, has invented certain new and useful Improvements in Apparatus and Processes for Making Chains, of which the following is a specification.

This invention relates to improvements in methods of and machines for making chain links and assembling them, more particularly to a method of and a machine for making chains having at intervals attachment or special links. The invention is an improvement upon the processes of and machines for making chains, examples of which are shown and described in the application for patent of Charles Parker, Serial No. 501,429, filed September 17, 1921, and in Letters Patent of the United States, No. 1,107,809 to S. D. Locke, patented August 18, 1914; and No. 1,107,831 to H. Osswald, patented August 18, 1914.

One object of the invention is to provide a novel method of making chains having special or attachment links.

Another object of the invention is to provide in a chain machine of the character described, means for interspersing or assembling with the plain links made on the machine, special or attachment links.

Elevator or conveyor chains are generally made up of sections or lengths of plain links between which are provided special or attachment links carrying wings or projections adapted to support or propel buckets, slats, conveyor elements or the like. In chain machines, prior to the Parker machine, it was customary to make the plain links and the special or attachment links on separate machines and to intersperse by hand the latter links in the chain or between sections of plain links.

This invention provides an improved method of manufacturing chains particularly adapted for elevating or conveying purposes, and to this end means are provided for (1) feeding a strip of metal step-by-step forwardly and transforming the strip into connected plain sprocket chain links; (2) accelerating or hastening, preferably at predetermined intervals, the feed-

ing of the connected plain links so that said connected plain links are fed forwardly a plurality of steps while the strip of metal is fed forwardly one step; and (3) feeding to or inserting in between the last formed plain link and the forward portion of the strip of metal, a partially formed special link having a wing attachment or projection, whereby the transforming steps upon the strip of metal may be continuous to successively complete the link formation on the plain links and to simultaneously complete the link formation on the special link, incorporating the special link in the chain between two plain links.

When a special link is to be interspersed with plain links by practicing the method of the application of Charles Parker, Serial No. 501,429, filed Sept. 17, 1921, the feeding of the strip of metal is arrested while the connected plain links are fed a step forwardly to provide a space on the stationary die of the press to receive the special link. Consequently, for each special link inserted there is a cessation or break in the continuity of the steps of the method. The method of this invention provides for the interspersion of special or attachment links with plain links without breaking the continuity of the operations necessary to the transformation of a strip of metal into connected plain links.

Other objects and advantages of the invention will be obvious from the following description of the construction and operation of a machine embodying the invention in connection with the accompanying drawings wherein I have shown one form of construction merely.

Fig. 1 is a front view, partly in section, of a machine embodying the invention;

Fig. 2 is a sectional view on line 2—2 in Fig. 1, looking in the direction of the arrows, omitting the countershaft and disclosing in side elevation the mechanism for feeding the partly completed special or attachment links to the duplicate finishing portion of the dies by which the plain links are made;

Fig. 3 is a fragmentary view of said attachment link feed mechanism detached, as when seen from the rear of the machine.

Fig. 3^a is a detail view of a portion of said attachment link feed mechanism.

Fig. 4 is an enlarged sectional view, partly in side elevation of the strip feed mechanism 5 of the machine;

Fig. 5 is an enlarged front view of the forming dies, extracting mechanism, and sizing mechanism;

Fig. 6 is an enlarged partly sectional view 10 of the dies for making the plain links and finishing the attachment links, showing them in section with a strip of metal between them, and also showing a portion of the sizing or stretcher mechanism;

Fig. 7 is an edge view of a strip of metal in 15 process of formation into a chain, some formed and coupled plain links being shown, and disclosing a special or attachment link (shown more clearly in Fig. 8) in position 20 to be incorporated in the chain;

Fig. 8 is a top plan view of the metal strip, special or attachment link, and plain links shown in Fig. 7;

Fig. 9 is a bottom plan view of the 25 movable die and the sizing or stretcher mechanism;

Fig. 10 is a top plan view of the stationary die and that portion of the feed mechanism for the special or attachment links associated 30 therewith, a special or attachment link being disclosed in position to be fed to the duplicate finishing portion of the dies;

Fig. 11 is a bottom plan view of a strip of metal showing scoring;

Fig. 12 is a section on line 12—12 in Fig. 13;

Fig. 13 is a plan view of a portion of the link extracting mechanism;

Figs. 14 and 15 are detail views of 40 fragments of the link extracting mechanism, showing how the feed of the connected links can be accelerated or hastened at predetermined intervals;

Fig. 16 is a front view of the metal strip 45 guide; and

Fig. 17 is a section on line 17—17 in Fig. 13.

In the drawings, 1 indicates an entirety, 50 the main frame of the machine comprising uprights 2, 3 and a bed 4 arranged between the uprights.

5 is a vertically reciprocatable slide mounted to move up and down in guides 6, 7 on the main frame.

8 is a main drive shaft transversely 55 mounted in bearings at the upper end of the frame. 9 is a countershaft transversely mounted upon the main frame and extending from one side to the other thereof. At one side of the main frame the countershaft carries a loose pulley 10, a fast pulley 11, and a fly wheel 12. At the other side of the frame the said countershaft has mounted loosely upon it a pinion 13 carrying one element 14 60 of a clutch, the other element 14' of which

is splined to the countershaft 9. Any suitable mechanism may be employed for throwing the longitudinally movable element 14' of said clutch into and out of engagement with the element 14, so as to transmit power 70 through the pinion 13. 15 is a gear wheel rigidly secured to said main shaft and in mesh with the pinion 13.

16 is an eccentric on the main shaft 8 connected by eccentric straps 17, 17', and pitman 18 to the slide 5.

As the construction of the press in itself forms no part of the invention, any known type of press having a reciprocatable slide and a bed or bolster beneath it may be readily adapted to operate the chain link forming and assembling mechanism to be herein-after described, and no further description of the press shown in the drawings is deemed necessary, as this particular press has been 85 chosen simply for illustrative purposes and not in any limiting sense.

Any suitable mechanism may be attached to the press for feeding the stock or strip of metal from which the chain links are to be 90 formed across the bed or bolster of the press. For the purpose of illustration I have, in the drawings, shown a feed mechanism of which 19 is a bracket secured to the standard 3 of the frame and having a horizontally disposed 95 platform 20, the inner end of which extends into a hole 3' through the standard 3.

21, 21, are side walls extending vertically upward, one at each side of the platform 20. 22 is a horizontally reciprocable slide 100 suitably mounted at either side in guideway in the said side walls 21. It rests upon a horizontally disposed friction plate 23 having downwardly extending pins 24, 24, each surrounded by a coil spring 25 bearing at its lower end against the platform 20 so as to provide a yielding support for the slide 22 which normally tends to press the slide against the upper walls of its guideways to insure the closing of the feed jaws, to be 110 hereinafter described, before the slide commences to move forward.

26 is a gripping piece carried by the slide 22, having an upwardly turned jaw 26' adapted to engage the under surface of the 115 stock or strip of metal to be fed across the bed or bolster.

27 is an oscillatable gripping dog having a jaw 27' adapted to engage the upper surface of the strip of metal to be fed, at a 120 point directly above the gripping jaw 26'. This gripping jaw 27 is pivotally mounted between upwardly extending lugs or ears 22', 22', on the slide 22, and carries an upwardly extending arm 28.

29 is a bell crank lever pivotally connected at 29' between the side walls 21 of the bracket 19.

30 is a rod pivotally connected at 30' to the upper end of the arm 28, and at 30^a to 130

the free end of the arm 29^a of the bell crank lever 29.

31 is an adjustable stop for limiting the throw of the arm 28 in clockwise direction.

5 This stop preferably consists of a screw extending through a threaded opening in a cross bar 22^a, which latter extends between the ears 22', 22' on the slide 22.

32 is a crank disc carried by the main drive shaft 8 and having a crank pin 32' to which is pivotally connected one end of a connecting rod 33, the other end of which is suitably connected to the free end of the arm 29^b of the bell crank lever 29.

15 34, 34 and 35, 35 are straightening rolls for the strip of metal or stock. These rolls are horizontally disposed and suitably mounted between the side walls 21, 21 on the bracket 19. A strip of metal, indicated by 36, is directed between the rolls 34, 34, and 35, 35 and between the gripping lips 26' and 27'. The dog 27 and arm 28 are shaped and proportioned to have a slight rocking motion relative to the slide 22, so

25 that in normal operation, as the connecting rod 30 is drawn to the right in Figs. 1 and 4, the gripping jaw 27' is rocked out of engagement with the upper surface of the strip of metal 36. The arm 28 then engages the stop 31 and the slide 22 recedes with the connecting rod 30. Upon the reversal of travel of the rod 30, it rocks forward the upper end of the arm 28 and causes the gripping jaw 27' to engage the upper surface of the strip 36, thereby gripping the said strip firmly between the jaws 26' and 27', and the slide 22 and strip 36 are together fed forward.

40 Any suitable dies or forming elements may be employed for striking up and forming each chain link from a strip of metal and coupling it to the next preceding link. In the drawings I have shown the use of two rigid dies for this purpose which are capable 45 of use in connection with the features of the present invention, one of said dies being movable and the other stationary.

Of the die and forming mechanism herein shown, 47 represents as an entirety the movable die, it being suitably connected to the slide 5.

48 represents a bolster or die bed for the stationary die. It is detachably secured to the bed 4 in any suitable manner. 49 represents as an entirety a stationary die suitably secured in the die bed 48.

60 The dies 47 and 49, which cooperate with each other to form and assemble the links, are arranged in longitudinal alinement with the line of feed of the strip 36 and are properly centered relative to said line of feed.

50, 51 are scoring knives or chisels arranged at the right hand end of the movable die 47 and adapted to impart lines of score

to the upper surface of the strip of metal, and 52, 53, are corresponding scoring knives or chisels carried by the stationary die 49 and arranged to impart lines of score 52', 53', respectively, to the under surface of the strip of metal, (see Fig. 11), each of which lines is directly beneath a line of score 50' or 51' (see Fig. 8), imparted by one of the upper scoring knives.

Of the dies 47 and 49, 54 is a severing and crimping element on the upper die having a convex crimping surface. It is arranged to cooperate with a cutting and bending knife 55 on the lower die. The lower die is recessed at 56 in front of the cutting knife 55 and beneath the severing and crimping element 54. The metal of the stationary die 49 in front of the recess 56 is cut away along the inclined line 57 to permit a section of the metal of each link blank to be bent downwardly by the severing and crimping element 54 before it has been severed at one end by the combined action of this element and knife 55.

58 is a curved forming or crimping element on the movable die 47, about which the metal for forming the smaller end bar or pintle of each link is bent or crimped. In front of this finger 58 is a recess 59, and in front of it is an irregular shaped end bar 95 forming punch element 60 consisting of two substantial quarter circles 60', 60^a.

61 is a forming and bending projection on the stationary die, it being adapted to enter the recess 59 in the movable die. 61' is a shoulder on the projection 61 adapted to fold or crimp the metal for the small end of the link against the curved end of the element 58 on the movable die.

62 is a scoring knife on the stationary die 105 adapted to impart a transverse score to the strip of metal along the line of severance of two links which are to adjoin each other and in conjunction with the forming corners 61^a, 61^b, is adapted to force the metal of the link 110 to follow the quarter circles 60', 60^a, on the former 60. This scoring knife 62 is in vertical alinement with the line of intersection of the said two quarter circles of the punch element 60. In advance of the said punch element 60 the movable die is recessed as indicated at 63 to allow clearance for the free upturning of the long lip of the metal blank for a link, which at this step of its formation projects upwardly from the metal strip. At 64 the stationary die is recessed to receive a cutting or severing knife 65 on the movable die, the edge 64' being a knife edge to work in conjunction with the knife 65 to sever the metal strip. Immediately in front of the cutting knife 65, the movable die is shaped as indicated at 66 to complete the

125 rounding and formation of the small end bar of each link in cooperation with the recessed section 67 of the stationary die.

At 68 the movable die is recessed for the purpose of engaging the longer section or lip of metal turned up from the central portion of each link blank and bending, curling 5 and conforming it to the cylindrical shape desired, at the same time causing it to encircle the small end bar or pintle of the link in front of it, thereby coupling or attaching these links together. The stationary die is recessed at 69 to cooperate with the recessed portion 68 of the movable die in the final shaping and forming of the large end bar of each link.

70 is a projection or mandrel extending 15 transversely across the recessed portion 69 of the stationary die. It serves to prevent the ends of the lips of metal forming the large end or sprocket bar of each link from engaging with each other, and to space them 20 apart a predetermined distance.

The recess 68 and recess 69 with mandrel 70 comprise the finishing portion or station on the dies for the plain links. Just beyond 25 said finishing portion or station is a duplicate finishing portion constituted by the similar recess 68' in the movable die and 69' in the stationary die, the latter recess having a mandrel 70' which is a duplicate of the mandrel 70.

30 71 is a strip gage for centering the metal strip 36 relatively to the forming dies as it is fed forward, it preferably consisting of a bar of metal arranged transversely on the stationary die bed and suitably secured in 35 position a little distance from the scoring chisels 52 and 53. In the top of this bar of metal is a V-shaped groove 71' with the axis of the V in the vertical central longitudinal plane of the dies. The walls of this 40 V-shaped groove are preferably elevated somewhat above the horizontal plane of the stationary die and the width of the groove at its middle vertically is preferably of the width of the standard size strip to be used 45 with the set of dies to which the gage is attached. The taper of this gage allows for variation in width of the strip of metal 36, so as to insure the proper centering of the strip despite its variation in width.

50 Mechanism of any suitable character, is employed for extracting and guiding the formed chain links out of the machine, and this chain link extracting mechanism includes mechanism indicated as an entirety 55 at 37, capable of accelerating or hastening the feed of the connected links at preferably predetermined intervals. For illustration, I have shown a chain guide 76 comprising two bars 76', 76", rigidly secured at their inner ends to the die bed 48, and projecting into the opening 32 through the adjacent wall of the main frame of the machine. These bars are longitudinally grooved and recessed as indicated at 76" to constitute a 60 guide way for the chain. The bars are re-

cessed at 76° to receive a cover plate 76' which is pivotally connected at 76° between upwardly projecting ears 76' of the said guide bars. 76" is a thumb nut extending through a slot 76" in the cover plate 76' and 70 detachably fitted into the guide bar 76" for the purpose of holding down the cover plate.

77 is a sprocket wheel arranged between and projecting between the guide bars 76', 76". It is carried by a shaft 77' mounted in 75 bearing blocks 77", each detachably secured to one of the aforesaid guide bars. 77" is a pawl carrying arm loosely mounted on the shaft 77'. 77" is a pawl pivotally connected to the arm 77". 77" is a ratchet wheel rigidly secured to the shaft 77' and having its teeth in the plane of the pawl 77". 77" is a lug or projection carried by the slide 5. It is pivotally connected at 77" to a rod 77", the lower end of which is pivotally connected 85 at 77" to the pawl arm 77".

38 is a cam arm pivoted on the frame of the machine as at 39; 40 is a spring normally holding the cam arm in upright position; 44 is a screw securing the spring 40 to the machine frame; 41 is a pin carried by the ratchet wheel 77" and 42 is a pin carried by the pawl 77".

78 is a spring having one end secured at 78" to the frame of the machine and its other end bearing against the teeth of the sprocket wheel 77" to form a frictional resistance to the rotation of the latter.

The upper end of the cam arm 38 is adapted to be engaged by the pin 42 on the pawl 77", when the cam arm is in upright position and the slide descends so that the pawl can successively pass back over but a single tooth of the ratchet wheel 77", whereby the chain link extracting mechanism will normally feed the connected links one step while the strip of metal is fed forwardly one step. The pin 41 on the ratchet wheel 77" is adapted to advance against the cam arm 38 to move it on its pivot away from the ratchet wheel in such manner that the pin 42 will clear the cam arm at the predetermined interval to pass back over two teeth of the ratchet wheel 77" when it is desired to feed the connected chain links a plurality of steps forwardly while the strip of metal is advancing a single step. See Figs. 14 and 15. When the pin 41 passes the cam arm 38, the spring 40 returns this arm to its normal position.

Any suitable mechanism may be employed for the purpose of correcting the size and pitch of the chain links. The size and pitch correcting mechanism is indicated as an entirety by 79. 79' is an arm extending forward from and preferably detachably secured to the movable die 47. This arm 79' has formed preferably integrally with it, a downwardly extending finger 79" which is pointed at its lower end as indicated at 79".

the rear surface 79^c of the said pointed finger being shorter than and at a greater inclination to the horizontal than the front surface 79^a of the said finger. This finger 79^a, is arranged to enter the sprocket opening in the last link but two of the links formed in the machine. 79^e is a block or finger pivotally connected at 79^f in the bifurcated end of the arm 79'. This block or finger extends downwardly beneath the arm 79', as indicated at 79^g and is adapted to enter the sprocket opening in the link next preceding the link entered by the finger 79^a. 79^h is an adjustment screw fitted in the finger 79^e and adapted to extend on the rear side of the latter and bear against the arm 79'. Its purpose is to adjust the said finger about the axis of the pivot 79^f and toward or from the finger 79^a. The adjustment wheel 79ⁱ for the screw 79^h 20 has a toothed or serrated periphery 79^j. 79^k is a lock pawl extending through an opening in the forward projection 79^l of the finger 79^e and engaging with the periphery of the thumb wheel to hold the wheel at any 25 point of adjustment. 79^m is a spring bearing at one end against the lock pawl 79^k and having its other end secured at 79ⁿ to the finger 79^e.

The distance between the front wall of the 30 downward extension 79^c of the finger 79^e and the rear wall of the finger 79^a remains substantially constant when the machine is in operation. If a link is shorter in pitch than it should be, these sizing fingers will bring it up to proper pitch by stretching it.

The mechanism for correcting the size and pitch of the chain links can obviously be of a construction different from that illustrated, for example, there could be a plurality of fingers 79^a.

The operation of the machine as thus far described will be readily understood. A strip of metal 36 is directed through the feed mechanism until the gripping jaws 26', 27', of the feed mechanism can engage with it. Power is then applied through the counter-shaft 9 to actuate the strip feed mechanism and slide 5. The strip is guided and centered by the gage so as to lie properly between the dies 47 and 49. When the slide 5 descends the scoring knives impart to the upper surface of the strip of metal, lines of score, and the scoring chisels likewise impart lines of score to the under surface of said strip. When the slide next ascends, the feed mechanism feeds forward the strip of metal one step and the first forming elements of the dies operate on the strip. The strip is fed forward step-by-step at each elevation of the slide, the dies acting on each link blank to form a completed link. After the first completed link has been formed, the operator extracts it from the dies and positions it to be coupled to the next succeeding link. The operator continues to extract and

advance the links thus formed and coupled together until the first one of said links is engaged by a tooth on the sprocket wheel 77. Thereafter the extracting mechanism operates to automatically extract the chain links 70 from the dies and advance them one step at a time. As the slide descends after the last formed link has been extracted by the extracting mechanism, the pitch correcting mechanism properly centers said link relative to the final link forming elements of the dies. The pitch correcting or sizing fingers operate at each descent of the slide to enter two coupled links in the chain guide to stretch said links up to gage, if required. 80

As already explained, when the pin 41, carried by the ratchet wheel 77^d is holding the cam arm 38 away from the ratchet wheel out of its vertical position as it is shown in Fig 15 so that the pawl 77^c passes back 85 over two teeth of the ratchet wheel 77^d when the slide descends, and the slide 5 ascends, the feeding of the connected chain links is accelerated or hastened as indicated, while the strip of metal moves ahead but a 90 single step. The result is that the link last formed and severed from the metal strip is moved two steps forward and the strip of metal is moved one step forward, leaving a link space on the duplicate finishing portion of the stationary die between the link sections which were advanced two steps and the metal strip which was advanced but a 95 single step.

The mechanism yet to be described operates to feed a partially completed special or attachment link to said duplicate finishing portion of the stationary die at the limit of that ascent of the slide 5 occurring when said link space is produced in the manner just described, and in position to be incorporated in the strand of chain. 100

Each partially completed special or attachment link is fed to the proper position at the duplicate assembling station on the stationary die, and the partially completed attachment links are preferably of the same size and of approximate construction of the metal strip or link section then at the first assembling station, except that each special link additionally has an attaching portion A, best shown in Figs. 8 and 10. It will be noted that the grooves 76^b in the bars of the chain link extracting mechanism (Fig. 17) are of sufficient depth to allow free passage of the attaching portions A. 110 115 120

Of the feed mechanism for the partially completed special or attachment links, 80 represents a pair of brackets mounted upon the rear faces of the upper portions of the uprights 2 and 3, respectively, and providing bearings for a rock shaft 81 extending from one side to the other of the main frame. 125

82 is a horizontally disposed arm fixed 130

upon the rock shaft 81 and extending rearwardly therefrom, having at its outer end a hook portion 82' adapted to hold one end of a coil spring 83 the opposite end of which 5 is held by a hook 84, supported in the bed 4.

An L-shaped member fixed upon the rock shaft 81 consists of a vertically disposed, downwardly extending arm 85 merging into a horizontally disposed, forwardly extending, preferably hook-shaped arm 85'. 86 is a vertically disposed ratchet rotatably mounted upon the rear face of the upright 3 of the main frame, as indicated at 86', and 10 87 is a pawl pivoted upon the slide 5 to engage the teeth 86^a of said ratchet. A 15 spring 87' and a stop 87^a on the slide 5 insure the proper working position of the pawl. The free end of the arm 85' is normally pressed against the rear face 86^b of the ratchet 86 by the influence of the spring 83, acting through the arm 82 and shaft 81. 20 86^c is a hole through said ratchet positioned to at intervals aline with the free end of the arm 85', to permit operation of the rock 25 shaft 81 by the spring 83.

88 is a block fixed upon the slide 5 and having a transversely disposed cam face 88' extending downwardly and forwardly of said block.

30 89 is a vertically disposed lever fixed upon the rock shaft 81 and extending downwardly therefrom; 89' is a roller mounted upon the lever 89 intermediate its ends and adapted to engage the cam face 88'. 90 is a horizontally disposed link the forward end of which is pivoted upon the lower end of the lever 89, as indicated at 90', and the rearward end of which is pivoted, as indicated at 90^a, upon the upper end of a lever 91, itself 35 pivoted intermediate its ends, as indicated at 91', upon a bracket arm 92 extending from the bed 4. The lower end of the lever 91 is pivoted, as indicated at 91^a, to a horizontally disposed L-shaped attachment link 40 feed member the arm 93 of which extends directly forward and beyond the front of the main frame and is slidably mounted in a bearing block 94 fixed to the left hand end of the stationary die holder 48 and 45 arranged beneath the chain guide of the link extracting mechanism, and the arm 93' of which extends a short distance from left to right in spaced relation to the front side of the stationary die holder.

50 95 is an attachment link receiving member positioned so that the top surface of its inner end 95' is flush with the top surface of the stationary die 49, and so that said inner end is in alinement with the position 55 on the stationary die to which the special or attachment links are to be at intervals fed. This receiving member 95 has at its side edges suitably shaped upturned flanges 95^a for the obvious purpose of guiding the 60 special or attachment links.

The attachment link receiving member 95 is also provided with a longitudinal slot 95^b adapted to slidably receive a pin 96 projecting upwardly from the free end of the arm 93' and attached, as indicated at 97, to 70 a feed plate 98 arranged between the flanges 95^a of the receiving member 95 and adapted to reciprocate upon said receiving members.

99 is a stop for the special or attachment 75 links, positioned upon the finishing portion of the stationary die.

As hereinbefore suggested, the special or attachment links may be partially completed on a separate machine and afterwards successively placed upon the receiving member 95 in front of the feed plate 98, as very clearly shown in Fig. 10 of the drawings, in position to be automatically fed at predetermined intervals to the proper 80 location on the finishing portion of the die. The attachment links may be so placed upon the receiving member 95 in any preferred manner either by hand or by suitable mechanism of some particular construction forming no part of the present invention. It 85 will be noted that the receiving member 95 is arranged to place the special or attachment links on the stationary die of Fig. 10 a little to the left of its final assembling 90 position, for a reason to be made clear.

The manner in which the attachment link feed mechanism operates will be obvious. Upon each upward movement of the slide 5 the pawl 87 engages a tooth 86^a of the ratchet 86 to rotate said ratchet one step. The coil spring 83 at all times tends to rotate the rock shaft 81 to swing the vertically disposed lever 89 forwardly but forward swinging of said lever is normally 100 prevented by the engagement of the hook 105 arm 85' with the rear face 86^b of the ratchet 86.

The ratchet 86 is made to have one less tooth than the ratchet wheel 77^a of the chain link feed mechanism and the hole 86^c in said ratchet 86 is positioned to be in alinement with the free end 85' of the arm 85 when the slide 5 is at the limit of that ascent occurring when the feeding of the connected links is accelerated or hastened to produce a link space on the duplicate finishing portion of the stationary die. For each pin 41 utilized, spaced at uniform or varying distances about the ratchet wheel 77^a, there must be a corresponding hole 86^c in the ratchet 86 as will be evident.

At the instant the slide is at the limit of that ascent just mentioned, the arm 85' enters the hole 86^c, the spring 83 operating 110 to rotate the rock shaft to swing the lever 89 forwardly, and said lever 89, through the instrumentality of the link 90, rotates the lever 91 on its pivot to cause the arm 93 of the attachment link feed member to 115 slide rearwardly in the bearing block 94, 120 to 125 130

and the arm 93' of said attachment link feed member to actuate the feed plate to move the attachment link at that particular time in the link receiving member, to its proper position on the duplicate finishing portion of the stationary die. The roller 89' is located to engage the cam face 88' when the lever 89 swings forwardly as just described, and upon the succeeding descent 10 of the slide, said cam face travels over said roller to swing the lever 89 backward to normal position, withdrawing the arm 85' from the hole 86'. As soon as the slide again starts to ascend, the pawl 87 rotates the ratchet 86 a sufficient distance to remove the hole 86' from its position of alignment with the free end of the hook arm 85', before the higher portion of the block 88 has been sufficiently elevated to release the roller 89'. The movement of the vertically disposed lever 89 to normal position, obviously, returns the feed plate to its normal position, that is, to the position in which it is shown in Fig. 10.

25 As the slide 5 descends when a special or attachment link is on the duplicate finishing portion of the stationary die, the surface 79° of the correcting finger 79^a, engaging a connected link and forcing it slightly rearwardly, against the inserted special or attachment link, causes said link to have its proper assembling position on the duplicate finishing portion of the stationary die. See Figs. 7 and 8, wherein the strip metal, connected chain links, and special link are shown in their relation at the instant after the special link was placed on the duplicate finishing portion of the stationary die, and Fig. 6 wherein the stationary and movable die are shown at the instant a special link is incorporated in the strand of chain.

It is to be noted that the attachment link feed mechanism does not operate until after the link extracting mechanism has advanced the plain links two steps and the strip of metal has been fed forwardly one step, so that there is no possibility of interference by the plain links with the ready feeding of the attachment links. It is to be further noted that the elements of the stationary and movable dies constituting the duplicate finishing portion or station in the machine connect only the attachment links to the strand of chain, the elements of said finishing portion making no impression upon the plain links as they pass through the duplicate finishing or assembling station.

60 Many alterations in the construction, and many apparently widely differing embodiments and applications of the invention will suggest themselves to those skilled in the art of making chain making machines and elevator or attachment chains, without departing from the scope and spirit thereof.

The disclosures and descriptions herein are purely illustrative, and are not intended to be in any sense limiting.

What I claim is:

1. The method of making chains having special links which consists in transforming a strip of metal into similar links, interspersing special links with said similar links and successively connecting all of said links simultaneously with the performance of operations of transforming said strip of metal into additional similar links. 70

2. The method of making chains having special links, which consists in transforming a strip of metal into successive similar links, interspersing partially completed special links with said similar links and successively connecting all of said links simultaneously with the performance of operations of transforming the strip of metal into 75 additional similar links. 80

3. The method of making chains having special links, which consists in forming a series of similar links from a strip of metal, connecting certain of said similar links together, interspersing special links with said similar links, and connecting said special links with adjacent links of the chain simultaneously with the performance of operations of transforming said strip of metal 90 into additional similar links. 95

4. The method of making chains having special links, which consists in the simultaneous acts of fastening a partially completed special link to a preceding similar link, completing the partially completed special link, and performing a plurality of different similar-link-formation steps on the part of the blank strip following the special link. 100

5. The method of making chains having special links which consists in transforming a strip of metal into similar links, of interspersing special links with said similar links and successively connecting all of said links 110 concurrently with the performance of transforming operations upon the strip of metal. 105

6. The method of making chains having special links, which consists in the operations of transforming a strip of metal into 115 a section of several connected similar links and of connecting a special link with said section concurrently with the performance of transforming operations upon the strip of metal. 120

7. The method of making chains having special links, which consists in transforming a strip of metal into connected similar links, interspersing special links with said similar links and connecting said special links in the strand of chain and between certain of said similar links concurrently with the performance of transforming operations upon the strip of metal. 125

8. The method of making chains having 130

- special links, which consists in transforming a strip of metal into sections of several similar links each, interspersing partially completed special links with said similar links and incorporating said special links in the strand of chain and between said sections concurrently with the performance of transforming operations upon the strip of metal.
10. 9. The method of making chains having special links, which consists in the operations of transforming a strip of metal into sections of several connected similar links each, of interspersing partially completed special links with said similar links before at least one of the similar links is completed and of successively connecting said special links in the strand of chain and between said sections concurrently with the performance of transforming operations upon the strip of metal.
15. 10. The method of making conveyor chains, which consists in providing plain links by forming step-by-step operations upon a strip of metal, in providing conveyor links, and in connecting each conveyor link as provided with the next preceding plain link simultaneously with the performance of operations upon the strip of metal, whereby the conveyor chain can be composed of strands constituted by at least one plain link and one conveyor link.
20. 11. The method of making conveyor chain, which consists in providing plain links by forming step-by-step operations upon a strip of metal, in providing conveyor links, and in connecting all of the links as provided concurrently with the performance of additional link forming operations upon the strip of metal.
25. 12. The method of making conveyor chain progressively, which consists in providing plain links by performing step-by-step operations upon a strip of metal, in providing special links, and in then simultaneously connecting at least one plain link and one special link in a strand of chain.
30. 13. The method of making chain, which consists in transforming a strip of metal into plain links, in interspersing special links with the plain links, and in connecting a plurality of links in the chain simultaneously with transforming operations upon the strip to provide strands each consisting of at least one plain link and one special link.
35. 14. The method of making chains having special links, which consists in successively transforming a strip of metal into connected similar links, feeding forward said similar links and strip during the intervals between transforming operations upon said strip, accelerating the feeding movement of said similar links at predetermined intervals to produce a link space between said connected links and said strip, and incorporating a special link in said link space and connecting the same with the next preceding link of said connected links.
40. 15. The method of making chains having special links which consists in successively transforming a strip of metal into connected similar links, feeding forward said similar links and strip during the intervals between transforming operations upon said strip, then accelerating the feeding movement of said similar links at predetermined intervals to produce a link space between the connected links and said strip, and incorporating a special link in said link space and connecting the special link between a pair of similar links.
45. 16. The method of making chains having special links, which consists in transforming a strip of metal into similar links, feeding forward said strip and links during the intervals between transforming operations upon said strip, severing each link as completed from the strip of metal and connecting it with the next preceding link, accelerating the feeding movement of said connected links at intervals to provide a link space between the connected links and strip of metal, positioning a special link in said link space, and connecting the special link in the chain between two similar links.
50. 17. The herein described process of forming a chain having special links which consists in feeding forward a strip of metal and progressively forming said strip step-by-step into connected links, feeding the connected links forward step-by-step, accelerating the feeding of said links to form a link space between certain of the links, feeding into said space a separate link corresponding in shape and size to the link section formed therein in said step-by-step formation, and then connecting said link in the chain.
55. 18. The method of making from sheet steel, drive chain having special attachments which consists in partially forming from such steel, links carrying the desired attachment, transforming step-by-step a strip of said steel into connected chain links, feeding the connected chain links ahead step-by-step with the operations upon the strip of steel, and periodically accelerating the feeding ahead of the connected chain links and inserting one of said attachment links between and connecting it to a pair of plain links.
60. 19. The method of making chain having special attachments, which consists in successively transforming a strip of metal into connected plain links, accelerating the feeding of the plain links at intervals to provide a link space between the strip of metal and the plain links, inserting a special link between said plain links and strip of metal, connecting said special link to said plain links.
65. 125

- links and simultaneously finishing an additional plain link and connecting it to said special link.
20. The method of forming chain progressively, which consists in feeding material to and between a plurality of bending and transforming elements, causing relative movement between portions of the material being transformed to form a space therebetween, feeding to such space other material for incorporation with and between said portions, and in then simultaneously connecting at least one of said portions and said other material in a strand of chain.
- 15 21. In a machine of the character described, the combination with means for transforming a strip of metal into similar links, of means for intermittently interspersing special links with said similar links, and means for connecting links operating simultaneously with the means for transforming the strip of metal.
22. In a machine of the character described, the combination with means for transforming a strip of metal, step-by-step into a series of similar links, of means for connecting special links with said similar links while said transforming means is operating.
- 25 23. In a machine of the character described the combination with means for transforming a strip of metal step-by-step into a series of similar links, of means for connecting special links between said similar links concurrently with the actual performance of transforming operations upon said strip of metal.
24. In a machine of the character described, the combination with means for transforming a strip of metal into a series of connected similar links, of means for interspersing partially completed special links between two of said similar links and for simultaneously connecting said special link with both of said similar links.
- 30 25. In a machine of the character described, the combination with means for transforming a strip of metal into similar links, of means for interspersing special links with said similar links and for simultaneously connecting a special link with a plurality of similar links.
26. In a machine of the character described, the combination with means for transforming a strip of metal into connected chain links, of means for connecting special links in the strand of chain at predetermined intervals and simultaneously with transforming operations upon said strip of metal.
- 35 27. In a machine of the character described, the combination with means for transforming a strip of metal into sections of connected similar links, of means for interspersing special links with the similar
- links and means for incorporating said special links in the strand of chain between said sections concurrently with the operation of said means for transforming the strip of metal.
28. In a machine of the character described, the combination with a stationary die and a movable die adapted to transform a strip of metal into a series of similar links, of means associated with said dies for connecting special links with said similar links while said dies are actually transforming said strip.
- 30 29. In a machine of the character described, the combination with a stationary die and a movable die adapted to transform a strip of metal into a series of connected similar links, of means associated with said stationary die for connecting partially completed special links with said similar links while said dies are transforming said strip.
- 35 30. In a machine of the character described, the combination with means for transforming a strip of metal into connected similar chain links, devices for feeding said strip of metal and connected links forward and means for accelerating the feeding of said connected links whereby a link space is produced between said connected links and strip, of means for feeding a special link to said link space and in position to be incorporated in the strand of chain.
- 35 31. In a machine of the character described the combination with means for transforming a strip of metal into connected similar chain links and means for feeding said strip and connected links forward step-by-step of devices for accelerating the forward feeding of said connected links at predetermined intervals while said strip is moved forward one step, and means for feeding a partially completed special link in position to be incorporated in the strand of chain.
- 35 32. In a machine of the character described, the combination with a stationary die and a movable die adapted to transform a strip of metal into connected similar chain links and devices for feeding said strip and connected links forward of devices for accelerating the feeding movement of said connected links to produce a link space between said dies, and means for feeding a partially completed special link to said space and in position to be incorporated in the strand of chain.
- 35 33. In a machine of the character described, the combination with a stationary die and a movable die adapted to transform a strip of metal into connected similar chain links, and devices for giving said strip and connected chain links step-by-step forward movement of devices for accelerating the forward feeding of said connected links, and means for feeding a special

link to said dies and in position to be incorporated with the connected links and links subsequently formed from said strip.

34. In a machine of the character described the combination of a stationary die and a movable die adapted to transform a strip of metal into connected similar chain links, and devices for giving said strip and connected links step-by-step forward movement, of devices for accelerating the forward feeding movement of said connected links while said strip of metal feeds forwardly one step, and means for feeding a special link to said dies between two similar links and for simultaneously connecting said special link with both of said similar links.

35. In a machine of the character described, the combination with means for transforming a strip of metal into similar chain links, devices for feeding said strip and similar links forward step-by-step, and means for severing each link as completed from the strip of metal and connecting it with the next preceding link, of devices for accelerating the forward feeding movement of said connected links while said strip of metal feeds forwardly one step whereby a link space is produced between said connected links and strip, and means for feeding a special link to said link space and in position to be incorporated in the strand of chain.

36. In a machine of the character described, the combination with means for transforming a strip of metal into connected chain links, said means including devices for simultaneously feeding said strip and links forward step-by-step of mechanism for accelerating the feeding movement of said connected links while said strip of metal feeds forwardly one step.

37. In a machine of the character described, the combination with devices for feeding a strip of metal and connected chain links forward step-by-step, of mechanism for accelerating the feeding movement of said connected links, said connected link feeding device including a ratchet wheel, a pawl adapted to engage said ratchet wheel, a cam arm normally in the path of said pawl whereby the pawl can rotate the ratchet wheel only one step, and said accelerating mechanism including a pin carried by said ratchet wheel and adapted to at intervals engage said cam arm to move it out of the path of said pawl whereby the pawl can rotate the ratchet wheel a plurality of steps.

38. In a machine of the character described, the combination with means for transforming a strip of metal into connected similar chain links, devices for simultaneously feeding said strip and connected links forward step-by-step, and means for at intervals accelerating the feeding move-

ment of said connected links while said strip of metal is fed forward one step, of mechanism for feeding special links in position to be incorporated in the strand of chain, said special link feed mechanism including a link receiving member associated with the strip transforming means, and devices for moving the special links from said receiving member and placing the same contiguous with a portion of the strip transforming means.

39. In a machine of the character described, the combination with a stationary die and a movable die adapted to transform a strip of metal into connected similar chain links, devices for simultaneously feeding said strip and connected links forward step-by-step, and means for at intervals accelerating the feeding movement of said connected links while said strip of metal is fed forward one step, whereby a link space is produced upon the finishing portion of the dies, of mechanism for feeding special links in position to be incorporated in the strand of chain, said special link feed mechanism including a link receiving member associated with said dies, and devices for moving a special link from said receiving member to each link space as produced.

40. In a machine of the character described, the combination with means for progressively transforming material into connected chain links, means for feeding such material into position for transformation means for feeding said connected links, means for accelerating the feeding movement of the means for feeding said connected chain links to provide a space between said chain links and material, means for feeding into such formed space a partly formed chain link whereupon the said inserted link is incorporated in the chain by said transforming means.

41. In a machine of the character described, the combination of means for transforming into connected chain links material from one source of supply, means for feeding said material to said transforming means step-by-step and at predetermined intervals, means for feeding said connected links, means for accelerating the feeding of the means for feeding said connected chain links for one step, separate means for feeding partly formed links from another source of material supply to said transforming means, and means correlated to effect the feed of the last mentioned feed means when the feed of said connected links is accelerated, whereby the resulting chain is formed from material from said plurality of sources of supply.

42. In a machine of the character described, the combination of a plurality of sources of chain material supply, means for transforming the material into a chain,

means for step-by-step feeding of one of said materials to said transforming means, means for step-by-step feeding of the chain, means for periodically feeding the other material to said transforming means, and means for accelerating the step-by-step chain feeding means while said other material feeding means operates.

43. In a machine of the character described, the combination of a pair of relatively movable dies, mechanism for actuating the same, sources of chain material supply, means controlled by said die actuating mechanism to separately feed the chain materials to and between said dies and for feeding the chain step-by-step out of the machine, and means for accelerating the speed of the chain when both feeding means operate.

20 44. In a machine of the character described, the combination of a pair of rela-
25 forming into connected chain links material
from one source of supply, means for feed-
ing said material to said transforming
means at predetermined intervals, means
for feeding said connected links, means
for accelerating the feed of a portion of
such material being transformed and sep-
30 arate means for feeding material partly
formed to said transforming means from
another source of supply between the por-
tions of the material in the transforming
means so as to effect therein formation of
35 chain from material from said plurality
of sources of supply.

45. In a machine of the character described, the combination of a source of chain material supply, a source of special chain link supply, means for transforming said material into chain and incorporating links from said special chain link supply therein, and means adapted to render the operation of said transforming and incorporating means concurrent and continuous.

45 46. In a machine of the character de-
scribed, the combination of a source of chain
material supply, a source of special chain
link supply, means for transforming said
material into chain and incorporating said
links therein, means for separately feeding
50 said material and said links to said trans-
forming means, means to effect the feed of
said material to said transforming means
when the link feeding means operates,
55 whereby chain is formed incorporating said
special links, and means adapted to render
the operation of said transforming and in-

corporating means concurrent and continuous.

47. In a machine of the character described, the combination with a stationary die and a movable die having means adapted to transform a strip of metal into a series of connected similar links, of separate means on said dies for connecting partially completed special links with said similar links. 60 65

48. In a machine of the character described, the combination with a stationary die and a movable die adapted to transform a strip of metal into similar links, including a finishing station for assembling said similar links and devices for feeding said strip and connected links forward during the transforming operation, of a duplicate finishing station on said dies, devices for at intervals providing a link space at said duplicate finishing station, and means for feeding a special link to said duplicate station in position to be incorporated in the strand of chain. 70 75 80

49. In a machine of the character described, the combination with a stationary die and a movable die adapted to transform a strip of metal into connected similar chain links, including a finishing station for said similar links on said dies, and devices for feeding said strip and connected links forward during the transforming operations, of devices for accelerating the feeding movement of said connected links to produce a link space upon said dies, a duplicate finishing station at said link space, and means for feeding a partially completed special link to said duplicate finishing station.

50. In a machine of the character described, a plurality of bending and transforming elements adapted to the purpose of forming chain progressively, means for feeding material to and between said elements, means for causing relative movement between portions of said material being transformed to form a space therebetween, means for feeding to such formed space other material for incorporation with and between said portions, and means for simultaneously connecting at least one of said portions and said other material in a strand of chain. 100 105 110
